CLAIM

We claim the ornamental design for a networked multimedia unit, as shown and described.

DESCRIPTION

FIG. 1 is a perspective view of a networked multimedia unit incorporating our new design;

FIG. 2 is a front view thereof;

FIG. 3 is a top view thereof;

FIG. 4 is a rear view thereof;

FIG. 5 is a bottom view thereof; and,

FIG. 6 is a left or right side view thereof.

The broken line showing on the networked multimedia unit is included for the purpose of illustrating only and forms no part of the claimed design.
